BRAKE BEAM AND SAFETY SUPPORT

Edward J. Simanek, Chicago, Ill., assignor to
 American Steel Foundries, Chicago, Ill., a corporation of New Jersey

Application August 27, 1947, Serial No. 770,876

14 Claims. (Cl. 188—210)

1

This invention relates to brake beams for railway car trucks and more particularly to truss type brake beams which are preferably of a composite or fabricated type.

The principal object of the invention is to provide a brake beam comprising a truss structure including tension and compression members, and a brake head member mounted on each end of said structure wherein one of said members is provided with a portion extending longitudinally of the beam and outboardly of the head for cooperation with a safety ledge on an associated truck side frame to prevent the beam from dropping to the ground in the event of failure of the hangers supporting the beam.

Another object of the present invention is to provide a brake beam of economical design and construction, wherein the parts are so arranged and connected as to afford an extremely rigid structure.

A further object of the invention is to provide a brake beam of the type described wherein the brake heads are afforded a seat against the associated end of the tension member and against a vertical wall of the compression member to afford a desired rigid connection therefor.

These and other objects of the invention will be apparent from the specification and the drawings, wherein:

Figure 1 is a fragmentary top plan view of one form of brake beam constructed in accordance with my invention;

Figure 2 is a front elevation of the portion of the brake beam shown in Figure 1 with a conventional hanger applied thereto and a portion of a side frame shown in transverse vertical section to illustrate the relationship between the beam and a safety ledge on the frame;

Figure 3 is a side elevation of the structure shown in Figure 2 with a portion of the frame broken away to more clearly illustrate the cooperation of the various parts;

Figure 4 is a fragmentary top plan view of another form of my brake beam;

Figure 5 is a view similar to that shown in Figure 2 illustrating in front elevation the brake beam shown in Figure 4;

Figure 6 is a fragmentary top plan view of still another form of my brake beam; and

Figure 7 is a view similar to that shown in Figures 2 and 5 showing the beam illustrated in Figure 6 in front elevation.

Describing the invention in detail and referring to Figures 1 to 3 inclusive, the brake beam, generally indicated 2, is of truss type comprising a

cambered U-section compression member 4 having a substantially vertical front wall 6 and integral spaced generally horizontal top and bottom webs or walls 8 and 10 extending rearwardly of the front wall from the top and bottom edges thereof, respectively. Adjacent each extremity thereof, the front wall 6 is provided with a longitudinally extending slot or opening 12 disposed substantially medially between the top and bottom edges of said front wall.

A round bar tension member 14 of uniform cross section throughout its length has at each extremity thereof a bent end 16 extending generally parallel to the adjacent portion of said front web 6 of the compression member and being snugly fitted into the associated opening 12, the end being so positioned in said opening 12 that the longitudinal center line of said end is disposed approximately in the vertical plane of the forward surface of the adjacent portion of said front web, as may be readily seen in Figures 1 and 3.

To provide a rigid connection between the tension and compression members 2 and 14, each end 16 of the tension member is secured to the front wall 6 in any convenient manner, preferably as by welding.

At each end of the beam is mounted a brake head, generally designated 18, comprising an arcuate front wall 20 to which is secured a brake shoe 22 by a key 24 in the usual manner.

Intermediate its ends the wall 20 is provided with a hanger socket 28 (Figure 3) for the reception of a loop hanger 30 adapted to afford support for the beam in the conventional manner from the side frame 32 (fragmentarily shown in Figures 2 and 3), as will be readily understood by those skilled in the art.

Top and bottom substantially vertical ribs 34, 34 are connected to the wall 20 and to an intermediate portion 36 (Figure 3) forming said socket 28 and to vertically spaced horizontal top and bottom webs 38, 38 extending rearwardly of the ribs 34 and portion 36 and defining with the rear extremity of said portion 36 a recess or cavity 40 (Figure 3) therebetween for the reception of the associated end 16 of the tension member and adjacent portion of the compression member. It will be noted that the rear extremity of the portion 36 is formed with a recess 42 affording a complementary fit for the portion of the tension member protruding forwardly of the compression member front wall 6 in the region adjacent said head, the outboard end of the tension member end 16 and recess 42 being terminated inboardly

of the outboard side of the head, as may well be seen in Figures 1 and 2, so that the front web 6 of the compression member is afforded a novel three point contact with the rear extremity of the portion 36, that is, outboardly of the end 16 and above and below said end respectively, said front web 6 seating flat against said rear extremity of the portion 36, as best seen in Figure 3. The head is secured to the compression member by rivets 44 and 46 connecting respectively the top web 8 of the compression member with the top web 38 of the brake head and the bottom web 38 of the brake head with the bottom web 10 of the compression member.

It will be understood that normally the brake beam is supported from the truck by the hangers. To prevent the beam from dropping to the ground in the event of hanger failure, the compression member of the beam has a portion 48 at each end thereof extending outboardly of the associated head for cooperation with a conventional safety ledge 50 disposed therebelow and formed on the adjacent side frame 32 integral with the tension member 54 thereof, the ledge extending laterally inboardly of said side frame and being of sufficient length to support the beam throughout the entire movement thereof longitudinally of the truck and being of sufficient width to prevent the beam from moving longitudinally off the ledge. Rearward movement of the beam is limited by abutment of the beam with the truck bolster (not shown).

In Figures 4 and 5, a modification is shown in which all the parts are the same as shown in Figures 1 to 3 inclusive, with the exception that the compression member 4 terminates at the outboard side of the brake head 18 and the tension member 14 has a portion 80 extending outboardly of the associated head for cooperation with the ledge 50 in the event of hanger failure. Accordingly, the longitudinal slot 12 in the front wall 6 extends to the extremity of the compression member wall 6 and the recess 42 extends to the outboard side of the head.

In Figures 6 and 7, still another modification is shown in which all the parts are the same as shown in Figures 1 to 3 with the exception that, as in the modification shown in Figures 4 and 5, the compression member 4 terminates at each end thereof approximately flush with the outboard side of the associated head, and that the bottom wall 38 of the head 18 comprises a lug or portion 100 extending laterally outboardly of the head for cooperation with the ledge 50 under the circumstances heretofore described. The lug 100 is reinforced by a rib 102 formed on the top side thereof and extending diagonally from the outboard edge of the lug 100 at a point intermediate the forward and rear edges of said lug to the forward edge of the lug at its juncture with the bottom web 38 of the head, the rib merging at its inboard end with the outboard side of the head.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. A truss type brake beam comprising a U-section compression member with a front web having a longitudinal approximately central slot adjacent its end, a tension member with a round-section end welded to said front web in said slot,

the center line of said end being disposed in the plane of said web, top and bottom webs integrally formed with and projecting rearwardly from said front web, a brake head member with top and bottom walls embracing said top and bottom webs and secured thereto rearwardly of said tension member end, a brake head member wall connecting said top and bottom walls and having engagement with said front web above and below and outboardly of said tension member end, said connecting wall having an arcuate socket receiving said tension member end and bearing against the surface thereof disposed forwardly of said front web, a hanger socket in said connecting wall forwardly of the first-mentioned socket, and a projection on one of said members extending outboardly of the outboard extremities of the other members for cooperation with an associated safety ledge.

2. A truss type brake beam comprising a U-section compression member with a front web having an approximately central slot extending longitudinally thereof, a tension member with a round-section end welded in said slot, the vertical center line of said end being disposed in the plane of said web, top and bottom webs integrally formed with and projecting rearwardly from said front web, a brake head member with top and bottom walls embracing said top and bottom webs and secured thereto rearwardly of said tension member end, a brake head member wall connecting said top and bottom walls and having engagement with said front web above and below said tension member end, said connecting wall having an arcuate socket receiving said tension member end and bearing against the surface thereof disposed forwardly of said front web, a hanger socket in said connecting wall forwardly of the first-mentioned socket, and a projection on one of said members extending outboardly of the outboard extremities of the other members for cooperation with an associated safety ledge.

3. A truss type brake beam comprising a U-section compression member having a front web and top and bottom walls extending rearwardly therefrom, a longitudinally extending slot in said wall adjacent each extremity of said beam, a tension member having a bent end at each extremity thereof and fitted into the associated slot and extending substantially parallel to the adjacent portion of said web with the longitudinal center line thereof disposed approximately in the vertical plane of the forward surface of said web, a brake head comprising rearwardly extending spaced webs receiving an end of said tension member and associated portion of said compression member therein and connected to said top and bottom walls of said compression member and seated against said end of said tension member and against said front web, one of said members having a portion extending outboardly of said head member for engagement with an associated safety support.

4. In a car truck, a side frame, a brake beam having a U-section compression member comprising a vertical front web and top and bottom walls extending rearwardly therefrom, a tension member having an end bent approximately parallel to said web and fitted into a slot in said web and connected thereto, said bent end having its longitudinal center line disposed approximately in the plane of the forward surface of said web, a brake head member secured to said top and bottom walls and comprising a hanger socket, a hanger extending through said socket and

adapted to support said beam, a projection on one of said members extending outboardly of said head, and a protuberance on said frame extending into engageable relationship to said projection for supporting said beam in the event of failure of said hanger.

5. A truss type brake beam structure comprising a U-section compression member with a front web and top and bottom walls extending rearwardly therefrom, a slot in said web at the extremity thereof extending longitudinally inwardly of said extremity, a round bar tension member having its end bent substantially parallel to said web and extending into said slot with the longitudinal center line of said end disposed approximately in the vertical plane of the forward surface of said web, said end being connected to said web, a brake head secured to said structure comprising a hanger socket, said compression member terminating flush with the outboard side of said head and said end having a portion thereof extending outboardly of said head for engagement with an associated safety support.

6. A truss type brake beam comprising a truss structure including a U-section compression member with a front web and top and bottom walls extending rearwardly therefrom, a slot in said web, a round bar tension member having its end bent substantially parallel to said web and extending into said slot and connected to said web, said end having the longitudinal center line thereof disposed approximately in the vertical plane of the forward surface of said web, a brake head secured to said structure comprising a hanger socket, said tension member terminating inboardly of the outboard side of said head and being received within a complementary recess in said head, said compression member extending outboardly of said head for engagement with an associated safety support.

7. A truss type brake beam comprising a truss structure including a U-section compression member with a front web and top and bottom walls extending rearwardly therefrom, a slot in said web, a tension member having its end bent substantially parallel to said web and extending into said slot and having a portion thereof protruding forwardly of the front surface of said web, a brake head secured to said structure comprising a hanger socket and seated against said end and said front web, said head comprising a projection disposed below said compression member and extending outboardly of said head for engagement with an associated safety support.

8. A brake beam having a U-section compression member comprising a vertical front web and top and bottom walls extending rearwardly therefrom, a tension member having an end bent approximately parallel to said web and fitted into a slot in said web and connected thereto, said end having its longitudinal center line disposed approximately in the plane of the forward surface of said web, a brake head member secured to said top and bottom webs and comprising a hanger socket, a hanger extending through said socket and supporting said beam, and a projection on one of said members extending outboardly of said head for engagement with an associated safety support.

9. A truss type brake beam comprising a truss structure including a U-section compression member with top and bottom webs and a front wall interconnecting said webs, a slot in said web, a tension member having its end bent sub-

stantially parallel to said web and extending into said slot and connected to said web and having a portion thereof extending forwardly of the front surface of said web, a brake head member having a hanger socket and seated against said end and the adjacent portion of said front web and secured to said structure, and a portion on one of said members extending outboardly of said head member for engagement with an associated safety support.

10. A truss type brake beam comprising a truss structure including a U-section compression member with a front web and top and bottom walls extending rearwardly therefrom, a slot in said web, a round bar tension member having its end bent substantially parallel to said web and extending into said slot with the center line of said end approximately in the vertical plane of the forward surface of said web, a brake head member secured to said structure comprising a hanger socket, and a projection on one of said members extending outboardly of said head for engagement with an associated safety support.

11. In a brake beam, a truss structure including a compression member comprising spaced webs and an intervening front wall with a slot therein, a tension member having an end bent approximately parallel to said wall and connected to said wall within said slot, said end having a portion thereof extending forwardly of the front surface of said wall, a brake head member secured to said structure, and a projection on one of said members extending outboardly of said head member for engagement with an associated support.

12. In a brake beam, a truss structure including a compression member with a front wall and a tension member having an end connected to said front wall, said end projecting at one side thereof forwardly of said wall, and a brake head secured to said structure and buttressed against said end and along spaced areas, including an area outboardly of said end, against said front wall.

13. A brake head comprising a member having spaced top and bottom walls and an intervening wall defining a brake beam receiving cavity, a support lug extending outboardly of said head and connected to said bottom wall, and a reinforcing element merging with the top side of said lug and the outboard side of said member, said element extending diagonally rearwardly of said head from the forward edge of said lug to the outboard edge thereof.

14. In a brake head, a member comprising a brake beam receiving cavity, support means for said head integral with said member and extending outboardly thereof, and reinforcing means for said support means merging with the top side thereof and with the outboard side of said member.
